UNITED STATES PATENT OFFICE.

FRANK TAMBORELLO, OF MILWAUKEE, WISCONSIN.

RAINCOAT.

Application filed April 19, 1926. Serial No. 102,944.

This invention relates to rain coats.

Objects of this invention are to provide a rain coat which is formed with a collar passing over the back of the wearer as a continuation of the lapels and lying flatly across the back of the coat under normal conditions without wrinkling or puckering so that it will provide additional protection for the coat across the back.

10 Further objects are to provide a novel form of collar which normally is flat but which may be nevertheless, drawn over the head and hat of the wearer and constricted by means of a draw string providing a restricted face opening with the terminal portions of the lapels juxtaposed and approximately vertical so that bunching or puckering at the chin or neck portion of the wearer will not occur.

20 An embodiment of the invention is shown in the accompanying drawings, in which:

Figure 1 is a front view of the rain coat with the collar laid out flat.

Figure 2 is a rear view thereof.

25 Figure 3 is a view showing the collar turned up over the head and hat or cap of the wearer.

Referring to the drawings, it will be seen that the coat comprises the body portion 1 provided with sleeves 2 and with lapels 3. It is further provided with a relatively large collar 4 which forms a continuation of the lapels and normally extends down over the back of the coat in a smooth and flat condition. It is to be noted, particularly from reference to Figure 1 that the lapels are partially separated from the collar by means of notches 5. These notches provide abrupt ends or terminal portions 6 for the collar for a purpose which will hereinafter appear. One of the lapels is provided with a buttonhole 7 and the other lapel, as indicated in Figure 3, is provided with a button 8 so that the lapels may be overlapped when desired, and buttoned or otherwise secured together.

50 The collar portion is provided with a sheath around its entire marginal edge and a draw string 9 is positioned within the sheath, and is preferably provided with knotted or enlarged ends to prevent inadvertent drawing of the draw strings into the sheath.

It is to be understood that the coat lapels and collar are to be made of a water proof material.

Under normal conditions, the collar is worn in the manner indicated in Figures 1 and 2, and thus protects the shoulders and back. However, when it is desired, to use the collar to protect the head and hat or cap of the wearer as indicated in Figure 3, it is merely necessary to swing the collar upwardly over the head and hat, and to thereafter, tighten the draw strings and tie their ends together. This provides a complete covering for the head and hat of the wearer except for a restricted face opening as shown in Figure 3. When the parts are positioned in this manner, the abrupt ends 6 of the collar are substantially vertical, and thus bunching of the material at the throat or chin of the wearer is prevented. Instead, a very comfortable condition exists and the garment is not rendered bulky at this point.

It will be seen that a novel form of rain coat has been provided which is so constructed that the collar normally hangs flat across the back of the wearer, but may be quickly turned up over the head and hat of the wearer and drawn into the position indicated in Figure 3.

Further, it is to be noted as described above, that even when the collar is used in this position, it is perfectly comfortable to the wearer and bunching of the material at the throat or neck of the wearer is avoided.

Although the invention has been described in considerable detail, such description is intended as illustrative rather than limiting as the invention may be variously embodied and as the scope of such invention is to be determined as claimed.

I claim:

A rain coat comprising a body portion having an open front provided with lapels, an elongated collar forming a continuation of said lapels and normally extending in a flat condition downwardly across the back of the coat, said collar having a sheath in its edge extending from the front ends of the collar completely around the back of the collar, a draw string extending freely and completely through said sheath and having projecting ends, said lapels and collar be-

ing partially separated by notches which collar approximately vertical and juxtaposed. ¹⁰
form abrupt terminal portions for the collar, the ends of the draw string projecting from the collar at said notches whereby the collar may be pulled over the hat and head of a wearer and the draw string may be tightened and tied to form a restricted face opening with the terminal portions of the

In testimony that I claim the foregoing I have hereunto set my hand at Milwaukee, in the county of Milwaukee and State of Wisconsin.

FRANK TAMBORELLO.
